G. H. FRASER

PULVERIZING MILL

Original Filed Mar. 17, 1917 2 sheets-sheet 1

INVENTOR:

George Holt Fraser

UNITED STATES PATENT OFFICE.

GEORGE HOLT FRASER, OF BROOKLYN, NEW YORK.

PULVERIZING MILL.

Application filed March 17, 1917, Serial No. 155,390. Renewed December 15, 1922.

To all whom it may concern:

Be it known that I, GEORGE HOLT FRASER, a citizen of the United States, residing at No. 226 Quincy Street, in the borough of Brooklyn, county of Kings, city and State of New York, United States of America, manufacturer, have invented certain new and useful Improvements in Pulverizing Mills, of which the following is a specification.

This invention relates to machines for crushing, grinding or pulverizing, and particularly to such machines having a revolving ring and internal crushing rolls which crush the material against the inner face of the ring.

In such machines the rolls are movably mounted and are pressed outwardly to resist a crushing pressure from the inner face of the ring, and the ring or one of the rolls is driven positively, the other crushing parts being revolved from the driven part by traction. If the ring is the driving part it may be mounted on a fixed axis and if one of the rolls is the driving part it may yieldingly support the ring loosely.

My present invention aims to provide improvements applicable to either of these types of pulverizers, and especially applicable to the loose ring type.

To this end my present invention provides various improved features and combinations which, in their preferred form as applied to a loose ring pulverizer, will be hereinafter more fully set forth with reference to the accompanying drawings, in which,

Fig. 1 is a front elevation of a loose ring pulverizer provided with the preferred form of my improvements, partly in vertical section on the planes of the lines 1—1 in Fig. 4;

Fig. 2 is a plan view of the feed hopper thereof;

Fig. 3 is a fragmentary horizontal section on the line 3 of Fig. 4;

Fig. 4 is a side elevation, partly in section cut on the planes of the lines 4—4 of Fig. 1;

Fig. 5 is an enlarged fragmentary side view partly broken away to show the feed chute, and in section on the planes of the lines 5—5 of Fig. 6, and

Fig. 6 is an enlarged fragmentary front elevation partly broken away to show a sec-

tion approximately on the planes of the lines 6—6 of Fig. 5.

Referring to the drawings A is the top casing, B is the bottom casing, C are the covers, D is the top bearing, EE are the lower bearings, F are the feed spouts, G is the feed hopper, H is the discharge outlet, a are the crushing rolls, b is the crushing ring, c are the roll shafts, d are the pressure springs, and e are the pressure screws of a pulverizer.

These parts may be of any suitable construction for a ring and roller pulverizer, those shown comprising a frame or casing composed of the separably connected top and bottom and the removable side covers, which afford an internal crushing chamber f in which the ring b revolves loosely on the rolls a, being generally supported by the top roll which is driven by a pulley g

on its shaft and which drives the ring and the other rolls by traction. The inner face of the ring is concave and the peripheries of the rolls are convex, and the material being crushed falls through the legs of the hopper G and descends through the spouts F on each side of the ring and flows on to its inner face where it is held by centrifugal force and carried successively past the rolls which crush it until it is fine enough to

discharge over the sides of the ring and descend into the chamber f to the outlet H. Pressure of the springs d is adjusted by the screws e until it is sufficient to overcome the crushing force of the material on the ring, and these springs yield to prevent breakage, and their respective bearings move to

equalize the crushing pressure between the rolls. Automatic locks h hold the screws e when adjusted, a shut off gate i is provided for starting and stopping the feed, and an adjusting gate j is used to regulate the feed. The casing has side apertures k through which the ring passes, and shaft slots l for permitting radial movement of the roll shafts.

According to the preferred form of my invention shown I provide a two duct feed hopper I in advance of the feed gate, a feed divider J in advance of the spouts, an adjustable chute K within the ring, movable or adjustable cheek pieces L at the sides of the ring, roll apertures M in the covers C, additional covers N therefor, rocking

dust guards O for the shaft slots sliding on

According to the preferred form of my invention shown I provide a two duct feed hopper I in advance of the feed gate, a feed divider J in advance of the spouts, an adjustable chute K within the ring, movable or adjustable cheek pieces L at the sides of the ring, roll apertures M in the covers C, additional covers N therefor, rocking dust guards O for the shaft slots sliding on

the covers N, double sliding spring pressed dust washers P sliding on the dust guards, movable collars Q supporting these washers, and lower bearings E having rigid upper arms suspended directly on and swinging positively from fixed pivotal axes above and near the center of gravity of these members so that these can be easily swung out of the way of the ring to remove the latter.

10 Pulverizers of this character discharge coarse and fine material and a sieve is used to separate the fine from the coarse and return the coarse to the pulverizer with fresh feed; and it is desirable that this returning coarse material should be pulverized as fast as it is returned so that fresh feed shall only be admitted after this coarse material is all pulverized.

15 My invention provides the multiple conduit hopper I which is preferably mounted movably removably or reversibly on the hopper G, and which has a vertical conduit R having a top inlet S and a bottom outlet T fitting into the mouth or regulating chamber U of the hopper G, which receives the coarse material returned from the sieve and delivers it in a vertical column or path to the chamber U of the hopper, and which has one or more side inlets V and a fresh feed 20 chamber or conduit W communicating therewith so that fresh feed must enter laterally against the descending column of returned material, the weight of which will automatically prevent inflow of fresh feed when 25 the conduit R is full of returned material, thus insuring that returned material shall be ground in precedence to fresh feed material so long as there is sufficient returned material to prevent ingress of fresh material, and that fresh material ingress shall 30 be controlled by the presence of the returned material. As shown the hopper I may be turned to any of four positions to dispose the fresh feed chamber W where convenient, and the hopper I fits removably in the hopper G for this purpose instead of being 35 formed integrally therewith.

40 Preferably I provide with or following the hopper I and between the regulating gate j and the feed spouts a movable or adjustable divider J for dividing the descending feed and apportioning it between the two sides of the ring so that it can flow on to the inner face of the ring at each side 45 in suitable proportions to hold the ring in position axially or to compensate for its unequal wear so that it will run true centrally of the chamber f. Any means movable transversely of the adjusting gate may be 50 used but I prefer to hinge the vertical damper J on the apex of the bifurcated legs of the hopper G so that its upper edge can be swung under the gate to cut the stream of material as desired for each leg, and to 55 adjust this damper by a spring operated

60 handle m engaging the teeth of a rack n and held therein by a spring o. Preferably a shelf p is provided above the damper. By properly regulating the damper undue axial stress of the ring or rolls may be obviated 70 and these parts can be approximately maintained in true positions. I preferably provide for adjusting the delivery of material on the inner face of the ring by the movable or adjustable chute K, which preferably 75 slides axially of the ring on feet q held on supports r, and has wide sides s projecting in pockets t in the spouts F to receive material descending through the latter. The chute has a high back u and a contracted 80 central mouth v which discharges the material centrally or at either side on the ring according to the adjustment of the chute. Preferably the chute is automatically adjusted 85 from the ring, as by levers w suspended from pivots x and having upper ends y struck by the ring when it moves excessively to one side, and lower ends z carrying the chute and removing it reversely of the movement of the ring to cause the chute 90 to feed material to one side or the other of the center of the ring in opposition to its axial movement for the purpose of resisting or correcting this.

95 Preferably I also provide movable adjustable or passive cheek pieces L at each side of the ring for limiting flow of material therefrom and preventing its contact with the casing. As shown the cheek pieces L each have a lug or projection X resting 100 on a ledge Y and are adjustably connected by a bolt Z so that they are passive relatively but can slide axially of the ring to adapt themselves to the position it assumes and can be adjusted to regulate fineness of 105 discharge or take up wear. The bolt Z extends from side to side of the die to connect the cheek pieces, and may be at either side of the die when the ring is a loose ring as shown, but cannot be exterior of the die as 110 shown unless the ring is loose, as the cheek pieces should have an inside diameter not greater than that of the ring.

115 The covers C preferably each have a roll hole M opposite each roll and large enough to pass the roll, and each hole is preferably closed by an auxiliary cover N having a shaft slot l, shown in Fig. 5, which is closed by the rocking dust guard O, shown in Figs. 1 and 4, which has a semi-cylindrical projection mounted slidingly in the bored out inner end of the adjacent bearing, as best seen in the lower left hand side of Fig. 1, to carry the weight of the dust guard from 120 the bearing and cause it to swing with the bearing while it is held against the cover N to close its shaft slot. Each dust guard has a clearance hole around the shaft, and between each bearing and dust guard are 125 two sliding washers P held apart by springs 130

- and supported on a revolving collar Q slidely mounted and feathered on the shaft to prevent leakage of dust along the shaft or of oil from the bearing. The shaft sus-
5 tains the sliding washers which work in slideways or sockets in the rocking dust guards so that they cannot revolve but are free to slide and prevent leakage as the shaft wears into the bearing metal bushing.
- 10 The dust guard O has a projection or shoulder surrounding its convex or semi-spherical projection which is opposite and adjacent to the cylindrically bored inner lip or end of the adjacent bearing E, as shown in Fig. 1, against which this lip abuts if the bearing moves inwardly, so that these parts constitute reciprocal stop provisions for limiting movement of the bearing axially through the medium of the dust guard 15 itself; but I prefer to utilize these only as emergency stop provisions and also provide additional provisions preferably proportioned to normally space the bearings slightly away from the dust guard so that 20 the latter will not have to carry the axial stress of the bearing while sliding on the stationary cover N, and these additional stop provisions are preferably spaced beyond the edge of the sliding dust guard and 25 opposite the stationary cover so that their movement and stress is independent of the dust guard and sustained by the stationary cover opposite the roll aperture which it closes. These additional means may be any 30 suitable reciprocal provisions for movably guiding the bearing from the stationary cover, as for example the stop roller shown on the bearing E, Fig. 1, which rides on the stationary cover outwardly of the side edge 35 40 of the dust guard as shown in Fig. 4 so that it will roll on the stationary cover opposite the roll aperture closed by the latter, and thus sustain the bearing axially and normally prevent it from pressing the dust guard too tightly against the cover, so that the dust guard can normally slide under the pressure of its springs only, but should the rollers wear or be removed the dust guard itself will resist inwardly axial displacement of the bearing.
- 45 In operation the ring revolves so that its side beneath the feed hopper descends and coarse material descends vertically through the conduit R and fresh material enters laterally when possible. Speed of feed is adjusted by the gate j, material is divided between the opposite sides of the ring by the divider J, and is distributed on the ring by the chute K. The cheek pieces prevent the 50 material from spilling off the ring, and it is carried around with the ring and successively crushed by the rolls until fine enough to flow between the sides of the ring and the cheek pieces. Any roll is removable by swinging back its bearing, removing its roll plate 55 60 65 and withdrawing the roll and shaft axially. To remove the ring the three bearings are swung back, one side cover is removed with its spout and small covers N, and the ring is moved out axially through the ring aperture k.
- 70 It will be seen that this invention provides improvements which can be readily and advantageously availed of in whole or in part, and it will be understood that the invention is not limited to the particular details of construction, combination or use, nor to the particular type of pulverizer set forth and shown as illustrating its preferred form, since it can be employed in whole or 75 in part according to such modifications and with such types of pulverizers as circumstances or the judgment of those skilled in the art may dictate without departing from the spirit of the invention.
- 80 85 What is claimed is:
1. In a mill of the type described, a grinding roll and a die, in combination with a casing for the same having a side aperture, a roll axle in said aperture having a bearing 90 without the casing, a cover for said aperture surrounding the axle, a dust guard on said axle adjacent the said cover, and a revolving collar on said axle between said dust guard and said bearing.
- 95 2. In a mill of the type described, a grinding roll and a die, in combination with a casing for the same having a side aperture, a roll axle in said aperture having a bearing 100 without the casing, a cover for said aperture surrounding the axle, a dust guard on said axle adjacent the said cover, and a sliding rotating collar slidely mounted on said axle between said dust guard and said bearing.
- 105 3. In a mill of the type described, a grinding roll and a die, in combination with a casing for the same having a side aperture, a roll axle in said aperture having a bearing 110 without the casing, a cover for said aperture surrounding the axle, a dust guard on said axle adjacent the said cover, and a collar splined to said axle between said dust guard and said bearing.
- 115 4. In a mill of the type described, a grinding roll and a die, in combination with a casing for the same having a side aperture, a roll axle in said aperture having a bearing 120 without the casing, a cover for said aperture surrounding the axle, a dust guard on said axle adjacent the said cover, a non-rotative washer on said axle between said dust guard and said axle bearing, and a rotative collar mounted on said axle between said bearing and said washer and sustaining the latter.
- 125 5. In a mill of the type described, a grinding roll and a die, in combination with a casing for the same having a side aperture, a roll axle in said aperture having a bearing 130 without the casing, a cover for said aperture

- surrounding the axle, a dust guard on said axle adjacent the said cover, a non-rotative washer on said axle between said dust guard and said axle bearing, and a sliding rotating collar slidably mounted on said axle between said bearing and said washer and slidably engaging said washer.
6. In a mill of the type described, a grinding roll and a die, in combination with a 10 casing for the same having a side aperture, a roll axle in said aperture having a bearing without the casing, a cover for said aperture surrounding the axle, a dust guard on said axle adjacent the said cover, a non-rotative 15 washer on said axle between said dust guard and said axle bearing, and a collar splined on said axle between said bearing and said washer and bearing against said washer.
7. In a mill of the type described, a grinding roll and a die, in combination with a 20 casing for the same having a side aperture, a roll axle in said aperture having a bearing without the casing, a cover for said aperture surrounding the axle, a dust guard on said axle adjacent the said cover, a pair of non-rotative washers on said axle between said 25 dust guard and said axle bearing, and a rotating collar mounted on said axle between said washers.
8. In a mill of the type described, a grinding roll and a die, in combination with a 30 casing for the same having a side aperture, a roll axle in said aperture having a bearing without the casing, a cover for said aperture surrounding the axle, a dust guard on said axle adjacent the said cover, a pair of non-rotative washers on said axle between said 35 dust guard and said axle bearing, and a rotating sliding collar slidably mounted on said axle between and bearing against said washers.
9. In a mill of the type described, a grinding roll and a die, in combination with a 40 casing for the same having a side aperture, a roll axle in said aperture having a bearing without the casing, a cover for said aperture surrounding the axle, a dust guard on said axle adjacent the said cover, a pair of non-rotative washers on said axle between said 45 dust guard and said axle bearing, and a collar splined on said axle between and bearing against said washers.
10. In a mill of the type described, a grinding roll and a die, in combination with a 50 casing for the same having a side aperture, a roll axle in said aperture having a bearing without the casing, a cover for said aperture surrounding the axle, a dust guard on said axle adjacent the said cover, a pair of non-rotative washers on said axle between said 55 dust guard and said axle bearing, and a collar splined on said axle between and bearing against said washers.
- 60

11. In a mill of the type described, a grinding roll and a die, in combination with a 65 casing for the same having a side aperture, a roll axle in said aperture having a bearing without the casing, a cover for said aperture surrounding the axle, a dust guard on said axle adjacent the said cover, a pair of non-rotative washers on said axle between said 70 dust guard and said axle bearing, axially yielding means between and pressing said washers away from one another, and a collar mounted on said axle between said washers.

12. In a mill of the type described, a 75 grinding roll and a die, in combination with a 80 casing for the same having a side aperture, a roll axle in said aperture having a bearing without the casing, a cover for said aperture surrounding the axle, a dust guard on said axle adjacent the said cover, a pair of non-rotative washers on said axle between said 85 dust guard and said axle bearing, axially yielding means between and pressing said washers away from one another, and a sliding collar slidably mounted on said axle between and bearing against said washers.

13. In a mill of the type described, a 90 grinding roll and a die, in combination with a 95 casing for the same having a side aperture, a roll axle in said aperture having a bearing without the casing, a cover for said aperture surrounding the axle, a dust guard on said axle adjacent the said cover, a pair of non-rotative washers on said axle between said 100 dust guard and said axle bearing, axially acting spaced springs between and pressing said washers away from one another, and a collar splined on said axle between and sustaining said washers.

14. In combination, an annular axially 105 movable die revolving in an approximately vertical plane and having an internal crushing face, a movable and rotatable crushing roll within and eccentric of said die and having a peripheral crushing face reciprocal to the inner face of said die, means for revolving one of said parts, means for supplying material to be crushed to said parts, and means within and movable axially of 110 said die for adjusting the position axially of said die at which such material is delivered on to the inner face of said die for varying the position of said die axially.

15. In combination, an annular axially 115 movable die revolving in an approximately vertical plane and having an internal crushing face, a movable and rotatable crushing roll within and eccentric of said die and having a peripheral crushing face reciprocal to the inner face of said die, means for revolving one of said parts, means for supplying material to be crushed to said parts, means for delivering such material on to the 120 inner face of such die from both sides of 125

the latter, means for varying the quantity of such material supplied to such die, and means for apportioning the quantity of such material delivered at the respective 5 sides of said die for varying the position of said die axially.

In witness whereof, I have hereunto

signed my name in the presence of two subscribing witnesses.

GEORGE HOLT FRASER.
